UNITED STATES PATENT OFFICE

102,640

DESIGN FOR A TRIMMING FOR RECEPTACLES FOR CIGARETTES OR OTHER ARTICLES

William J. Reilly, Attleboro, Mass., assignor to Evans Case Company, a corporation of Massachusetts

Application November 25, 1936, Serial No. 66,142

Term of patent 3½ years

To all whom it may concern:

Be it known that I, William J. Reilly, a citizen of the United States residing at Attleboro, county of Bristol, and State of Massachusetts, have invented a new, original, and ornamental Design for a Trimming for Receptacles for Cigarettes or other articles, of which the following is a specification, reference being had to the accompanying drawing, forming a part thereof.

In the accompanying drawing Figure 1 is a top plan view of a trimming for receptacles for cigarettes or other articles showing my new design. Fig. 2 is a side elevation thereof.

I claim:

The ornamental design for a trimming for receptacles for cigarettes or other articles as shown.

WILLIAM J. REILLY.
